UNITED STATES PATENT OFFICE

GEORGE L. DANFORTH, JR., OF CHICAGO, ILLINOIS, ASSIGNOR TO OPEN HEARTH COMBUSTION COMPANY, OF CHICAGO, ILLINOIS, A CORPORATION OF DELAWARE

OPEN-HEARTH-FURNACE PORT

Application filed October 9, 1922, Serial No. 593,276. Renewed April 11, 1930.

This invention relates to a new and improved open hearth furnace port construction and more particularly to a construction of this character provided with a plurality of 5 ports upon each end of the furnace.

As is well known in the art, open hearth furnaces are double ended and are reversed in operation, each end serving alternately to introduce the fuel and air and to carry off the 10 products of combustion. The products of combustion largely exceed in volume the incoming air and fuel and consequently the ports must be designed with a view of carrying off the larger volume of the products of 15 combustion. It is, however, necessary for efficient operation that the incoming air and fuel be properly intermingled and controlled to form a relatively short, hot flame properly directed upon the bath of metal in the furnace.

Certain furnaces have been designed with damper controlled ports upon each end of the furnace, these ports being closed off upon the incoming end and serving on the outgoing 25 end to aid in carrying off the products of combustion. A furnace of this type is shown in the patent to McKune, No. 1,339,855, dated May 11, 1920. In these furnaces, two dampers are required, one in each of the supplemental 30 discharge passages, and these dampers not only complicate the installation but due to their water-cooling involve considerable heat losses.

It is desirable in open hearth furnaces to 35 separate the incoming fuel at each end of the furnace into a plurality of small streams since the small streams will more readily mix with the air and will give a more rapid combustion. Another advantage of divided streams lies in their greater efficiency in melting down a 40 charge. A single central flame will be broken up by impinging upon the charge and will be deflected to the walls and roof. This results 45 not only in inefficient heating but in damage to the furnace walls and roof. On the other hand the divided streams will meet upon the piled up charge and will efficiently melt it down. In the construction of separate ports 50 the furnace side walls may be utilized as port

walls so that but little additional brickwork is required over a single port furnace.

It is an object of the present invention to provide a new and improved open hearth port construction comprising a plurality of 55 ports at each end of the furnace, certain of the ports being associated with air and gas passages and additional discharge ports being provided.

It is a further object to provide a construction of this character in which the air streams are directed through the individual ports and in which they straddle the fuel streams.

It is also an object to provide a construction of this character in which the auxiliary 60 discharge ports connect the hearth to the incoming air passages and in which said auxiliary 65 ports are damper controlled.

Other and further objects will appear as the description proceeds.

I have illustrated a preferred embodiment of my invention in the accompanying drawings, in which—

Figure 1 is a vertical longitudinal section of one end of a furnace constructed according 75 to my invention;

Figure 2 is a horizontal half section taken on line 2—2 of Figure 1; and

Figure 3 is a horizontal half section taken on line 3—3 of Figure 1.

Referring to the drawings, the ports 6 lead to the furnace hearth 7, being inclined inwardly toward the center line of the furnace. The rear end of these ports is enlarged at 8 and joins the chamber 9. The vertical passages 10 connect the chamber 9 and the air slag pocket 11. The gas slag pocket 12 is connected by upstakes 13 to the elbows 14. These elbows join the gas ports 15 which extend through the chamber 9 and into the rear portion 8 of the ports 6. As shown in the drawing, the elbow 14 is provided with the water-cooled shell 16 and the inner refractory lining 17. The ports 15 are provided with the water-cooled shell 18 and with the refractory 95 lining 19 and are covered by the refractory material 20.

The upper portion of the chamber 9 is connected to the hearth 7 by the passage 21 which extends substantially the full width of the 100

furnace. This passage 21 is controlled by damper 22 which moves in water-cooled guides 23. The damper is moved vertically by means of cable 24, extending over pulley 25.

- 5 In the operation of the furnace, upon the incoming end, the damper 22 is lowered. The air, which may be preheated in any suitable regenerators, is led from the air slag pocket 11 through passage 10 to the chamber 9. 10 From the chamber 9 it passes through the enlarged rear ends 8 of the ports 6. It straddles the fuel port 15 and mingles with the fuel in the ports 6. The fuel comes in through suitable regenerators to slag pocket 12 and 15 passes up through passages 13 and elbows 14 to the fuel ports 15. On issuing from the fuel ports, it is straddled by and mingled with the air stream as has been stated. The ports 6 are so designed and proportioned as to give 20 an adequately controlled and properly directed flame.

Upon the outgoing end of the furnace, the damper 22 is raised and the products of combustion may pass directly through passage 21 25 to the upper end of the chamber 9, and thence through passages 10 and slag pocket 11 to the regenerators. A portion of the products of combustion will enter the ports 6 and this portion will again be divided, a part of it 30 passing around the gas ports to the chamber 9 while the remainder enters the gas ports and passes down through the gas slag pocket to the gas regenerators.

The water-cooled elbows 14 are subjected 35 to considerable erosion by the heated products of combustion and are consequently lined with refractory material. They are, however, made removable so that they may be replaced without the necessity of tearing down 40 any portion of the furnace. The form of construction shown makes it possible to introduce the flame through comparatively small ports which are designed to properly intermingle and direct the air and gas 45 streams. At the same time, the provision of the damper controlled passages permits the products of combustion to be carried off without the use of auxiliary draft producing appliances.

50 One specific embodiment has been shown by way of example, but my construction may be modified to adapt it to varying conditions within the scope of the appended claims.

I claim:

- 55 1. In an open hearth regenerative furnace, a plurality of separated ports at each end of the furnace, gas and air passages connected with said ports, and a damper controlled discharge port located above said ports. 60 2. In an open hearth regenerative furnace, a plurality of separated ports at each end of the furnace, gas and air passages connected with said ports, and a damper controlled discharge port located above said ports, said

discharge port being connected to said air passages.

3. In an open hearth regenerative furnace, a plurality of separated ports at each end of the furnace, a fuel passage terminating adjacent each such port, an air passage overlying the end of each fuel passage, the combined fuel and air stream being directed toward the port, and a discharge port located adjacent said ports. 75

4. In an open hearth regenerative furnace, a plurality of separated ports at each end of the furnace, a fuel passage terminating adjacent each such port, an air passage straddling the end of each fuel passage, the combined fuel and air stream being directed toward the port, and a damper controlled discharge passage located above said ports. 80

5. In an open hearth regenerative furnace, a pair of ports at each end of the furnace, a chamber in the rear of each pair of ports communicating with said ports, air passages leading to said chamber, and a gas passage extending through said chamber into the rear 85 of each of said ports. 90

6. In an open hearth regenerative furnace, a pair of ports at each end of the furnace, a chamber in the rear of each pair of ports communicating with said ports, air passages leading to said chamber, a gas passage extending through said chamber into the rear 95 of each of said ports, and an auxiliary discharge passage connecting the furnace hearth with each chamber. 100

7. In an open hearth regenerative furnace, a pair of ports at each end of the furnace, a chamber in the rear of each pair of ports communicating with said ports, air passages leading to said chamber, a gas passage extending through said chamber into the rear 105 of each of said ports, and an auxiliary discharge passage located above each pair of ports and connecting the furnace hearth and the chambers. 110

8. In an open hearth regenerative furnace, a pair of ports at each end of the furnace, a chamber in the rear of each pair of ports communicating with said ports, air passages leading to said chamber, a gas passage extending through said chamber into the rear 115 of each of said ports, and a damper controlled auxiliary discharge passage located above each pair of ports and connecting the furnace hearth and the chambers. 120

Signed at Chicago, Illinois, this 4th day of October, 1922.

GEORGE L. DANFORTH, JR.
